Edward N. Pagels ATTORNEY.

UNITED STATES PATENT OFFICE.

JOHN H. MAIN, OF DETROIT, MICHIGAN.

GREASE CUP.

1,419,282.

Specification of Letters Patent. Patented June 13, 1922.

Application filed January 13, 1921. Serial No. 436,867.

To all whom it may concern:

Be it known that I, JOHN H. MAIN, a citizen of the United States, and residing at Detroit, in the county of Wayne and State of Michigan, have invented a new and Improved Grease Cup, of which the following is a specification.

This invention relates to that type of lubricators known as grease cups, and its 10 object is to provide a device of this character which may be filled by means of so-called "grease guns" without the necessity of removing the cup or any of the parts.

This invention consists of a cylindrical 15 body having a top and bottom, the bottom being formed with a threaded discharge connection and the top being apertured to receive a rotatable inlet tube, the tube being threaded to fit in a threaded piston and 20 the outer end of the tube being closed with a check valve.

It also consists in forming the piston of a pair of circular disks, a cup shaped member of very thin resilient metal between 25 them, and an internally threaded tube having circumferential shoulders to hold the disks together.

It further consists of the details of construction illustrated in the accompanying 30 drawing and particularly pointed out in the claims.

In the drawing, Fig. 1 is a central vertical section of this improved grease cup. Fig. 2 is a section on the line 2—2 of Fig. 1.

35 Similar reference characters refer to like parts throughout the several views.

The present invention is designed to take advantage of the fact that cylindrical bodies may be drawn from circular sheets 40 and that although the internal circumferences of such bodies are substantially equal throughout their length, the cross sections are not exactly the same throughout their length. This has been found objectionable 45 as it made reaming or otherwise machining them necessary. The filling of grease cups by means of grease guns has been attempted but with poor success as the usual cup must be taken apart to permit filling.

50 In the present cup, 1 is a cylindrical shell having an end 2, preferably produced by drawing from a circular sheet of metal, and while the end 2 is centrally perforated, the lower end of the shell is threaded to 55 fit within the threaded flange 3 of the base 4 which is formed with a threaded con-

nnection 5. This base may also be formed by drawing dies from a circular disk.

A tube 6 is rotatable in the perforation in the end 2 and has a collar 7 secured 60 to it by any desired means, a pin 8 being shown. The lower and main portion of the tube is threaded to receive the threaded hub 9 of the piston which consists of the two disks 10 and 11 held in position by the 65 shoulders 12 and 13, by means of which the circular heads 14 and 15 of the intermediate cup-shaped piston members are held in position. To these circular heads are attached the cylindrical skirtings 16 70 and 17 which are very thin and resilient. I prefer these skirtings to be only a few thousandths of an inch thick and to be slightly flaring so that the lower edge of the outer skirting will closely fit the inner 75 surface of the body 1. The metal of these skirtings is so thin that it will conform to every irregularity in the shell 1 and the diameter of the lower edge of the outer skirting is just above that of the shell so 80 that leakage between them of grease is prevented.

After the upper end of the tube 6 has been passed up through the aperture in the top 2, a winged collar 18 is clipped onto the 85 projecting end, a check valve preferably in the form of a bale 19 is dropped into the reduced end, a spring 20 is positioned by means of a proper tool and the pin 21 is inserted to hold the collar and spring in 90 place. The upper end of the tube is preferably formed with a collar 22 to retain a grease gun.

When the grease cup has been mounted on a machine or bearing, the piston is drawn to 95 the top of the body by turning the tube, after which a grease gun is connected to the upper end of the tube and grease is forced down into the cup through the tube 6, the check valve 19 being forced down thereby to permit its passage. A grease gun such as the Gullborg Patent No. 1,307,734, dated June 24, 1919, when provided with the coupling shown by the Piquerez Patent No. 1,276,108, dated August 20, 1918, may be used 100 for this purpose. Thereafter the collar 18 and the tube 6 may be turned to force down the piston and to squeeze the grease out through the connection 5. The friction between the skirting of the piston and the body 110 1 is greater than between the tube 6 and the hub 9.

In some cases it is impossible to attach the grease gun to the outer end of the tube 6, and to render this grease cup of general application I attach a small connector 23 to the body 1 near the bottom 4, as shown in Fig. 1, this connector being formed with a check valve 19, a spring 20 to hold it in place, and preferably with a small pin 21 to support the spring. The action of this connector is the same as above described.

The inner skirting 17 and its disk 15 may be omitted if found unnecessary with stiff greases and the various parts of the cup may be changed as to both design and proportion without departing from the spirit of my invention as set forth in the following claims.

I claim:

1. In a grease cup, the combination of a cylindrical shell, a bottom for the body having a discharge opening, a top for the shell provided with a central opening, a tube rotatable in the opening and a collar on the tube below said top, a second collar attached to the tube above the top, a check valve in the upper end of the tube to prevent the escape of the contents of the cup, said tube having a threaded exterior within the body, and a piston screwed onto the tube provided with a thin resilient skirting engaging the interior surface of the shell to prevent the rotation of the piston in the cup.
2. A piston for grease cups comprising a hub, a pair of supporting disks secured

thereon, and a plurality of thin metal disks between the supporting disks, said thin disks having cylindrical skirtings, one within the other, extending down from the circumference of said disks with the lower edge of the outer skirting adapted for engagement with the interior of the shell, and heads attached to said skirtings and secured between the disks.

3. In a grease cup, the combination of a cylindrical shell, a top and a bottom having a discharge opening, said top having a central opening, a screw threaded cylindrical member rotatable in the opening and having a threaded exterior within the body, means to rotate said cylindrical member, a piston screwed onto the cylindrical member and comprising a pair of supporting disks and a thin pressed sheet metal disk between the supporting disks and provided with a thin resilient skirting engaging the interior cylindrical surface of the cup, said cup having an inlet opening through which grease may be introduced, and a check valve to normally close said inlet opening.

4. A piston for grease cups comprising a pair of circular disks, a plurality of thin metal heads between the disks and a thin resilient cylindrical skirting attached to the edge of each head, the outer skirting engaging the interior surface of the shell of the grease cup.

JOHN H. MAIN.
